UNITED STATES PATENT OFFICE.

DICK EDWARDS RADCLYFFE, OF HYTHE END, STAINES, ENGLAND.

FIBER-PREPARED MACHINE.

No. 839,198.

Specification of Letters Patent.

Patented Dec. 25, 1906.

Application filed December 28, 1905. Serial No. 293,650.

To all whom it may concern:

Be it known that I, DICK EDWARDS RADCLYFFE, manufacturer, a subject of the King of Great Britain, residing at Hythe End, 5 Staines, in the county of Middlesex, England, have invented a Fiber-Preparing Machine, of which the following is a specification.

This invention relates to a combination gill-box and fiber-softening machine for preparing and opening or otherwise treating fiber or fibrous material preparatory to combing, and is designed more especially for treating vegetable fibers, such as ramie, rhea, 10 china-grass, or the like, but may be used for treating or preparing any other fibers to 15 which same may be applicable.

I employ any suitable gill-box—such, for example, as that set forth in British Patent No. 7,404 of 1897, and according to the present invention I arrange and mount in combination with said gill-box a plurality of rollers advantageously arranged in pairs. For example, I find it advantageous to employ about twenty or twenty-one pairs of rollers, 25 (i. e., forty or forty-two rollers,) or thereabout, some of said rollers being fluted or ribbed or corrugated or otherwise formed other than smooth in any suitable manner, while others of said rollers may be plain rollers. For example, with twenty-one pairs of rollers six adjoining pairs may be fluted, (or other than plain,) and then one pair plain, and the next six pairs fluted, and the next pair plain, and so on. These plurality of 30 rollers are mounted just in front of the feed-apron leading to the gills on the gill-box part of the machine, and said rollers are advantageously set fairly close together in the longitudinal direction so as to occupy as little 35 space as possible, while the individual pairs of rollers are vertically (or otherwise) disposed relatively to one another and spring-mounted or weighted, &c., in such wise as to exert the desired crushing action or pressure 40 or softening action on the fibrous stems or straws or other fibrous material as it is being passed through same on its way to the gill-box, and thereby soften or act on such fibrous material so as to exert a very beneficial effect 45 thereon before same is acted on by the gills, which latter are thereby also enabled to

exert a beneficial effect on such fibrous material immediately after the latter has thus been subjected to such preliminary treatment in said plurality of pairs of rollers on 55 said machine, whereby the said fibrous material after it has passed through the gill-box will be found to have been very beneficially acted on by the complete combination-machine, and many advantages result, including saving of labor, as well as improvement in 60 the fibrous material.

The accompanying drawing shows part of the gills A of a gill-box with twenty-one pairs of rollers arranged and combined therewith 65 according to the present invention, so that the fibrous material on its way to the gill-box passes first through the said twenty-one pairs of rollers B B^X, some of which rollers—viz., each seventh pair of rollers B^X—are 70 shown as plain rollers, while all the other rollers B are shown as fluted rollers.

D is the feed-apron, on which the fibrous material is laid and by means of which the latter is fed in between the plurality of pairs 75 of rollers B B^X.

E is endless traveling belt, onto which the fibrous material is delivered from the said rollers B B^X and conveyed (fed) into the gill-box. 80

What I claim is—

In a device of the character described, the combination with the gill-box, of means for crushing and softening the fiber preparatory to combing, comprising a series of rollers arranged in pairs, one roller above the other and spring-pressed into close engagement, means for feeding the fibers between said rollers, means for receiving said fibers after passage through said rollers and delivering the same to the gill-box, said rollers being provided with fluted faces throughout the series and pairs of plain or smooth-faced rollers interspersed at fixed intervals throughout the series of fluted rollers, substantially as described. 85 90 95

In witness whereof I have hereunto set my hand in presence of two witnesses.

DICK EDWARDS RADCLYFFE.
